WINDOW OPERATOR OR SIMILAR ARTICLE

Lyle M. Northrup, New Hampton, Iowa, assignor to
Lynor Engineering, Inc.

Filed May 4, 1972, Ser. No. 250,473

Term of patent 14 years

Int. Cl. D8—09.

U.S. Cl. D8—153

FIG. 1 is a perspective view of the front and side of a window operator or similar article showing my new design;

FIG. 2 is a front elevational view;

FIG. 3 is a rear elevational view;

FIG. 4 is a side elevational view from the left of FIG. 2;

FIG. 5 is a side elevational view from the right of FIG. 2; and

FIG. 6 is a bottom plan view.

I claim:

The ornamental design for a window operator or similar article, substantially as shown.
